CLAIM

The ornamental design for a locking mechanism on collapsible crate, as shown and described.

DESCRIPTION

FIG. 1 is an exploded perspective view of a collapsible crate containing a locking mechanism of this invention;

FIG. 1A is an enlarged perspective view of a connector on a side wall of the collapsible crate, taken in the circle on the side wall of FIG. 1;

FIG. 1B is an enlarged perspective view of a connector receptor on a bottom wall of the locking mechanism on collapsible crate, taken in the circle on the bottom wall of FIG. 2 is a perspective view of the crate in a semi-collapsible state;

FIG. 3 is a perspective view of the crate in a fully assembled state;

FIG. 4 is an elevational view of the fully assembled crate; FIG. 5 is a plan view of the top of the underside of the fully assembled crate; and

FIG. 5A is an enlarged perspective view of the locking mechanism comprising a twist lock connecting the side walls of the crate, taken in one of the circles on the corners of the crate shown in FIG. 5.

1 Claim, 4 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.
